UNITED STATES PATENT OFFICE

157,052

CORNER RADIO OR UTILITY SHELF

Harry Kaplan and Sidney Eidinger,
Brooklyn, N. Y.

Application August 2, 1948, Serial No. 147,896

Term of patent 3½ years

(Cl. D33—3)

To all whom it may concern:

Be it known that we, Harry Kaplan and Sidney Eidinger, citizens of the United States of America, residing at Brooklyn, in the county of Kings and State of New York, have invented a new, original, and ornamental Design for a Corner Radio or Utility Shelf, of which the following is a specification, reference being made to the accompanying drawing, forming a part thereof, in which

Figure 1 is a front elevational view of a corner radio or utility shelf, embodying our new design,

Figure 2 is an end view of the same corner radio or utility shelf shown in Figure 1,

Figure 3 is a top plan view of the same shelf shown in Figure 1, and

Figure 4 is a perspective view of our corner radio or utility shelf shown in Figures 1, 2 and 3.

We claim:

The ornamental design for a corner radio or utility shelf as shown.

HARRY KAPLAN.
SIDNEY EIDINGER.
